FUR DOLL

Sarah I. McLachlan and Wilbur D. McLachlan, both of
Rt. 5, Box 628-B, Oklahoma City, Okla. 73108

Filed Oct. 19, 1972, Ser. No. 300,586

Term of patent 14 years

Int. Cl. D21—01
U.S. Cl. D34—2 R

FIG. 1 is a top view of the fur doll showing our new design;

FIG. 2 is a bottom view of the doll of FIG. 1;

FIG. 3 is a front view of the doll of FIG. 1;

FIG. 4 is a rear view of the doll of FIG. 1; and

FIG. 5 is a side view of the doll of FIG. 1.

We claim:

The ornamental design for a fur doll, substantially as shown and described.
